US0D1072740S

(12) **United States Design Patent** (10) **Patent No.:** **US D1,072,740 S**
(45) **Date of Patent:** **** Apr. 29, 2025**

(54) **WIRELESS CHARGER**

- (71) Applicant: **Shenzhen Autral Technology Innovation Co., Ltd.**, Shenzhen (CN)
(72) Inventor: **Xinlong Wei**, Shenzhen (CN)
(73) Assignee: **SHENZHEN AUTRAL TECHNOLOGY INNOVATION CO., LTD.**, Shenzhen (CN)

(**) Term: **15 Years**

(21) Appl. No.: **29/898,482**

(22) Filed: **Jul. 27, 2023**

(51) LOC (15) Cl. **13-02**

(57) **CLAIM**

The ornamental design for a wireless charger as shown and described.

DESCRIPTION

FIG. 1 is a first perspective view of a wireless charger showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the article that form no part of the claimed design.

1 Claim, 8 Drawing Sheets
